UNITED STATES PATENT OFFICE.

ALBERT BROMLEY ALLEN, OF SANTA MONICA, CALIFORNIA.

FASTENER.

Application filed June 30, 1927. Serial No. 202,439.

This invention relates to fasteners for curtains, awnings and the like. The device is adaptable for securing the awning in position of service and in such a manner that the awning is likewise readily released from said fastener.

At the present time it is extremely difficult to secure the ordinary form of curtain or awning in position due to certain factors such as weather conditions, wherein the awning has become wet and tends to shrink. When this occurs it is almost impossible to fasten the awning. With my device, however, I am enabled to fasten the awning when the shrinkage thereof does not exceed a certain predetermined amount.

Other objects include a fastener of the character stated which is simple of construction, easy to operate and fool proof.

With the above and other objects in view, the invention consists in a novel and useful provision, formation, construction, association and relative arrangement of parts, members and features all as shown in certain embodiments in the accompanying drawing, described generally and more particularly pointed out in the claims.

In the drawing:

Fig. 1 is an elevation of the improved fastener, the eyelet part of which is shown associated with a curtain;

Fig. 2 is a side elevation of the fastener;

Fig. 3 is a cross sectional view on the line 3—3 of Figure 1;

Fig. 4 is a cross sectional view on the line 4—4 of Fig. 1; and

Fig. 5 is a side elevation of a modified form of fastener.

Corresponding parts in all the figures are designated by the same reference characters.

Referring now with particularity to the drawing, I have shown two forms of fasteners which I designate as entireties by A and B respectively. The form A will be described first and the same includes members *a* and *b*. The member *b* comprises an eyelet which is adapted to be secured to a curtain *c*. The member *a* comprises a base 1, stud 2, and arm 3. The stud 2 is adapted to swivel relative to the base, the base to this end being formed with a bore 4 and the said stud 2 is formed with a base portion 5 and a central part 6 depending from said base and received in the opening 4. An end of said part 6 may be upset as shown at 7 so as to cooperate with angular walls 8 bounding the opening 4. The said

stud is formed with a bifurcated portion 9. The lever 3 is formed with a cam slot 10 and said lever is received between the bifurcations of the stud being held in position relative to said stud by means of a pin 11, passed transversely through said bifurcated portion of the stud and the cam slot 10. In the present instance the lever is formed of a piece of strap metal which is bent intermediate its length in such a manner as to provide a handle portion 12 and two cooperating portions 13 and 14. The base 1 is likewise provided with transverse openings 15 whereby the said base may be secured to some retaining object, such as shown at 16, by means of screws or the like 17.

The device B is identical in construction with the device A with the exception of the lever. The device B includes the eyelet *b* as before and the stud member is designated as *d*.

The lever comprises a wire 20, the ends of which are secured together by twisting, as shown at 21. The said wire is provided with two spaced apart portions 22 and 23 joined together by a curved portion 24, and the pin 11 is received between the said spaced apart portions 22 and 23. It will be noted that the part 23 is bowed slightly at 25 and that both said parts 22 and 23 are formed with abrupt curved portions 26 and 27.

The operation of the device A is as follows: We assume that the ordinary form of drop curtain is used. Portions adjacent the edge of said curtain are provided with one or more eyelets *b*. The parts *a* will be placed along the wall or on the floor as the case may be. When it is desired to secure the curtain against movement, the handle 3 is moved so that the same may be passed through the eyelet *b*, as shown for instance in Fig. 2. If now the handle were moved in the direction of the arrow of Fig. 2, the eyelet would be moved down said handle and over the stud. The handle then could be moved relative to the eyelet in such manner as to straddle the eyelet as shown in Fig. 3. It is obvious that the cam slot in cooperation with the pin 11 will tightly secure the eyelet as between the base 5 of the stud and the said lever. An advantage of this device resides in the swivel movement allowed the stud. If the condition shown in Fig. 1 by a dotted line is assumed, it will be seen that the curtain is represented as having the eyelet off center with relation to the device *a*. It is a simple

- matter to insert the handle in the eyelet and then turn the handle, the stud permitting such a turning and the eyelet with the curtain is forced down the handle and over the stud.
- 5 The device B operates upon the same principle as the device A, and after the handle has been secured to the eyelet the handle may be moved relative to the pin 11 and the eyelet to lock the eyelet between the stud and the handle. The bowed part 25 acts to engage opposite portions of the eyelet. The abruptly bent portions 26 and 27 likewise act as a locking means for limiting movement of the handle when the handle is engaging the eyelet.
- 10
- 15

It is obvious that I have provided a device which renders the locking of an awning of any form a simple matter. In particular I have provided a device in which effort to 20 secure the awning is minimized. Devices which attempt to secure curtains or awnings and the like by passing the same over snap studs do not always function for the reason that the awning or curtain may be shrunk 25 and not permit a ready snapping thereof. My device, as has been stated, overcomes these faults. It is obvious that various changes, modifications and variations may be made in practicing the invention in departure from the particular showing of the drawing without departing from the true spirit thereof.

Having thus disclosed my invention, I claim and desire to obtain by Letters Patent:

30

35 1. In a fastener for curtains and the like,

comprising an eyelet adapted to be secured to the curtain and means secured to a further member for cooperation with said eyelet, said means comprising a stud, and a lever secured to said stud and slidable relative thereto; said lever being adapted to be passed through the eyelet for directing the eyelet on to said stud.

2. In a fastener for curtains and the like, comprising an eyelet adapted to be secured to the curtain and means secured to a further member for cooperation with said eyelet, said means comprising a stud, and a lever secured to said stud and slidable relative thereto; said lever being adapted to be passed through 45 the eyelet for directing the eyelet on to said stud, and cam means for said lever whereby when the lever is slid relative to the stud the eyelet may be locked as between said lever and the stud.

3. In a fastener comprising an eyelet adapted to be secured to a curtain and means adapted to be secured to a relatively stationary object and for securing said eyelet; said means comprising a swiveled stud, a lever formed with a cam slot, and means passed through said cam slot for securing the lever to the stud, whereby when the eyelet is upon said stud the said lever may be moved to cam the same into tight engagement with 60 the eyelet.

In testimony whereof, I have signed my name to this specification.

ALBERT BROMLEY ALLEN.
